BRUSH-HOLDER FOR ELECTRIC MACHINES

Leopold Peterlik, Vienna, Austria, assignor to
Uher & Co. Gesellschaft fur Apparatebau,
Vienna, AustriaApplication April 11, 1950, Serial No. 155,239
In Austria April 29, 1949

7 Claims. (Cl. 171—324)

1

This invention relates to brush-holders for electric machines.

The object of the invention is to provide an improved guiding of the carbon brush by which the friction between the brush and the compressing member or the wall of the brush-holder is minimized, and break down as a result of soiling is avoided due to the particular construction, and that in spite of the fact that the brushes are resiliently biased towards the side wall of the holder.

Closely fitting the brush in the brush-holder has not proved satisfactory. On the other hand a clearance in the holder effects undesirable consequences as vibrations and tilting over of the brush—particularly in case of reaching the critical number of revolutions, or if the commutator is not exactly circular—resulting into sparking and burning out of the copper segments. In order to overcome the said inconveniences it has already been proposed to bias the brush towards the opposite wall of the brush-holder by means of resilient members such as flat springs, yaws, or the like, which may be disposed in the brush-holder or in an opening of the wall of the same. With such constructions special provisions have proved to be necessary in order to prevent the guide members from failing or tilting, and to ensure symmetrical distribution of pressure. Therefore only a rather complicated construction is enabled to ensure sufficient safety of working with the said brush-holders.

With the said constructions, however, considerable frictional forces are involved, thus the brushes are not so easily movable as desired, and even self-stopping may occur.

The said defects may be partly overcome by provision of rollers or ball members rotatably mounted and adapted to transmit the pressure of guiding to the brush. The hitherto known constructions of the art referred to, however, likewise require a considerable constructional expenditure for carrying out the brush-holder and the means for pressure transmitting as well as supporting and guiding of the compression members, such as shown and described for instance in the Letters Patent of the United States No. 662,758 and 2,436,279.

According to the present invention, however, vibrations of the brush are eliminated in a simple way by providing one or more ball members or rollers of steel guided for free rotation, with sufficient clearance symmetrically arranged in holes of one of the walls of the brush-holder, the said holes tapering towards the inner face of the said wall, and a plate spring fixed to the outer face

2

of the said wall, and biasing the carbon brush towards the opposite wall of the brush-holder.

By these means the intended effect is forwarded in any respect as by the almost point-like contact in connection with the rolling friction, the unhindered, uniform and easy feeding of the brush is ensured even in case of comparatively high pressure of the spring, thus sticking fast and stopping being avoided.

Owing to the said very simple construction the brush is prevented from sticking fast even in case of the possibly worst soiling, as coal dust or other dust frequently collecting in machines with exhaust fan is prevented from depositing between the brush and the wall kept in a distance from the brush as well as between the latter and the guide members, and that due to the continuously changing positions of the balls or rollers.

Some embodiments of the invention are illustrated by way of example in the accompanying drawing, in which:

Fig. 1 is a perspective view of the brush-holder according to the invention,

Fig. 2 is a section taken on line II—II of Fig. 1,
Figs. 3 and 4 are perspective views of modified constructions of the brush-holder, and

Figs. 5 and 6 illustrate modifications of the holder using rollers instead of balls.

Referring to Figs. 1 and 2 the carbon brush 2 is inserted into a box 1, and is urged in the direction towards the commutator by a compression spring not shown in the drawing. Fig. 2 shows that the width of the brush is smaller than the inside width of the box. In the front wall of the box there are provided two conical holes 3 each containing a ball 4 of steel, which balls are forced to the brush 2 by a plate spring 5 fixed to the front wall of the box.

The holes are dimensioned such as to prevent the balls from dropping into the box when still empty. The diameter of the ball sufficiently exceeds the thickness of the wall, in order to ensure reliably urging the balls to the brush with a sufficient pressure even in case the width of the brush changes according to the tolerated inaccuracies happening in producing the same. By arranging two balls symmetrically with regard to the longitudinal axis reliable guiding is ensured, and the exertion of equal pressures to the balls is guaranteed by fixing the plate spring symmetrically between the two balls.

In the construction as shown in Fig. 3 there is provided a single ball disposed in the longitudinal symmetrical axis. Such simple construction has been found sufficient in case of a brush of small

width, or of a brush the sides of which have nearly equal length.

In the modified construction as illustrated in Fig. 4 there are provided four ball members 4 for guiding the brush, being biased towards the carbon brush by means of a common plate spring 5 symmetrically fixed with regard to the positions of the balls. In this example the particular construction of the opposite wall of the box may be noted, which may be provided with two or more ribs 6 preferably running in the longitudinal direction and being rounded or flattened.

As shown in Figs. 5 and 6 instead of steel ball members there may be used short rollers as has been mentioned already. In such case the holes in the front wall of the box have to be rectangular in shape.

According to the embodiment of the invention illustrated in Fig. 6 the means for guiding by balls or rollers may be applied to the leading and trailing walls, respectively, of the box in regard to the sense of rotation of the machine, the balls being disposed in at least two different planes perpendicular to the direction of feeding the brush. In this case a plurality of balls is provided in each of said opposite walls.

Provided the plate spring 5 is dimensioned in an adequate way the brush has proved to be kept in the holder box so quiet that a satisfactory and sparkless commutating is obtained even in case of using coal brushes of such poor qualities, the use of which would have hitherto brought about severe breakdowns.

The construction according to the invention has turned out well particularly in low voltage machines with comparatively great current density in the brushes, as well as in small motors with high numbers of revolutions, as the high frequency disturbances caused by sparking are eliminated to the highest degree.

What I claim as new and desire to secure by Letters Patent is:

1. A brush-holder for electric machines, comprising a container adapted to receive a brush, said container having a front wall provided with at least one hole, said holes being symmetrically arranged with regard to the longitudinal axis of the container and tapering toward the inner face of the wall, a rotatable member inserted with clearance in and held by each of said holes, a plate spring fastened to the outer face of said

front wall, for urging said rotatable members toward an opposite wall of the container.

2. A brush-holder as claimed in claim 1, in which the rotatable members consist of balls.

3. A brush-holder as claimed in claim 1, in which the rotatable members consist of rollers.

4. A brush-holder as claimed in claim 1, which comprises at least two rotatable members, and in which the plate spring is arranged symmetrically with regard to the rotatable members and acts uniformly on the same.

5. A brush-holder as claimed in claim 1, in which the wall opposite to the front wall, is provided with at least two longitudinally extending ribs.

6. A brush-holder for an electric machine, comprising a container adapted to receive a brush, said container having a front wall and an opposite wall, each provided with a plurality of holes tapering toward the inner face of the respective wall, a rotatable member inserted with clearance in and held by each of said holes, a plate spring fastened to the outer face of each of said front wall and opposite wall, for urging said rotatable members toward the interior of the container, the rotatable members being arranged in the direction of at least two different planes which are perpendicular to the feed direction of the brush to be fed by the brush-holder.

7. A brush-holder as claimed in claim 6, in which the rotatable members are arranged in the leading and trailing wall of the container, relative to the direction of rotation of the machine.
